(57) **CLAIM**

The ornamental design for a vehicle-mounted wireless charger, as shown and described.

DESCRIPTION

1. Vehicle-mounted wireless charger

1.1 : Front

1.2: Back

1.3 : Left

1.4 : Right

1.5:Top

1.6: Bottom

1.7 : Perspective

1.8 : Perspective

1.9 : Perspective

1.1 is a front view of a vehicle-mounted wireless charger showing our new design; 1.2 is a back view thereof; 1.3 is a left view thereof; 1.4 is a right view thereof; 1.5 is a top view thereof; 1.6 is a bottom view thereof; 1.7 is a perspective view thereof; 1.8 is another perspective view thereof; and 1.9 is another perspective view thereof.

The broken lines shown in the figures are for the purpose of illustrating portions of the vehicle-mounted wireless charger and form no part of the claimed design.
